TOY CARRYING AND RELEASING DEVICE FOR KITES

Filed April 4, 1947

UNITED STATES PATENT OFFICE

2,446,684

TOY-CARRYING AND RELEASING DEVICE
FOR KITES

Paul C. Armbrust, Columbus, Ohio

Application April 4, 1947, Serial No. 739,445

2 Claims. (Cl. 244—155)

1

My invention relates to toy kites, and has particular reference to a toy device, of the type adapted for attachment to a kite string for conveying droppable toys from the ground to a flying kite; whereupon the device serves to release the associated droppable toy to permit the latter to descend once again to the ground.

In the past, many devices of this general character have been employed for the purpose set forth, but such devices were subject to certain disadvantages in operation and in mechanical design. It follows therefore that the primary object or aim of my invention is to generally improve upon known and patented mechanisms of this character, and to provide a toy-carrying and releasing device for toy kites which is mechanically efficient, positive in operation, and economical in manufacture.

Heretofore, the principal difficulty encountered with devices of the character described, resides in the fact that the devices were subject to the accidental release of their associated droppable toy prior to reaching the desired point of release, which was substantially the point at which the kite is joined to the end of the kite string. Such accidental release being occasioned primarily by the tangling of the device with the kite string during its ascent; and also by the accidental striking of the release mechanism of the device during its ascent. Accordingly, it is another object of this invention to provide a toy-carrying and releasing device which incorporates means whereby such accidental release is eliminated, the same being provided with a trip, or releasing mechanism which functions to release an associated toy only upon striking a certain type of stop stationarily disposed upon the associated kite string at the desired point of release.

It is a further object of my invention to provide a device of this character which is economical to manufacture, resulting in a reduced cost to the ultimate child user.

These and additional objects and advantages of the present invention will become readily apparent with reference to the following descriptions and the accompanying drawing, wherein:

Fig. 1 is a perspective view of my improved toy-carrying and releasing mechanism occupying its operational position upon an associated kite string;

Fig. 2 is a top plan view of the device;

Fig. 3 is a side elevational view thereof;

Fig. 4 is a longitudinal vertical sectional view

2

taken through the device and disclosing the same in its open, toy-releasing condition.

Fig. 5 is a longitudinal sectional view taken along the line 5—5 of Fig. 3.

- 5 Referring more particularly to Fig. 1 of the drawing, it will be seen that the present invention makes use of a kite 1 which may be of any suitable type, and a kite string 2 extending from the kite body to a position on the ground. Fixed 10 to the kite string 2, by knots located adjacent thereto, is a stationary stop 3 formed with a beveled or conical shaped surface 4. The use of this stop 3 will be hereinafter explained in detail.
- 15 The toy-carrying and releasing device, comprises an elongated body 5 provided at its upper surface with a pair of spirally wound hooking devices 6, the latter being adapted for detachable engagement with the associated kite 20 string 2, whereby to permit longitudinal sliding movement of the body with respect to the string. Carried by the body 5 and depending therefrom, are forward and rear bracket members, 7 and 8 respectively. Each of the brackets 7 and 8 are 25 substantially U-shaped and are attached to the body by means of suitable rivets or pins 9. The brackets 7 and 8 slidably receive an elongated and forwardly projecting keeper 10, the latter being formed at its rearward end with a substantially U-shaped bail 11. The rearward bracket 8, is formed with a downwardly opening slot 12 and cooperates with the bail of the keeper 10 to provide a sliding latch adapted for the releasable attachment for an associated toy 30 13. The toy 13 may take the form of any suitable object such as a toy glider, as shown in the drawing, a parachute, or paper message, or any suitable toy device which is capable of being blown upwardly of the kite string under action 35 of the wind. It will also be understood that the toy article 13 must be provided with a substantially looped lead line 14, adapted for engagement with the bail portion of the keeper 10.
- 40 The forward end portion of the keeper 10 is formed as at 15, with an upwardly projecting shoulder, which is engageable with the forward tapered-nose portion 16 of the body to prevent the keeper from rearward longitudinal sliding movement, and to prevent accidental release of the associated droppable toy 13. The extreme 45 end portion of the keeper 10 terminates in an outwardly flanged and beveled striking surface 17, which, as shown in Fig. 3 of the drawing, is engageable with the cooperative beveled surface 4 50 of the stop block 3. It will be seen, that as the

body 5 travels upwardly of the associated kite string 2, the striking surface 17 of the keeper will ultimately strike the beveled portion of the stop 3, thereby disengaging the shoulder 15 from the pointed nose 16 of the body and exerting a backward longitudinal movement upon the keeper body 10. Upon backward longitudinal movement of the keeper 10, it will be seen that the bail portion 11 which carries the supporting loop of the toy article 13, will be slid backwardly within the rear bracket 8 to open the slot 12 formed in the rear bracket and to release the toy article 13. The backward movement of the keeper 10 is limited by a stop formed at the rear portion of the body. This stop 18 is substantially semi-conical in configuration, and provides a beveled surface similar to that of the stop 3, and functions as a secondary releasing stop for a second identically formed releasing device as the latter progresses longitudinally of the kite string after the first carrying and releasing device rests at the original stop 3. Referring particularly to Fig. 3 of the drawing, it will be seen that the body portion 5 is provided with an inwardly tapered recess 19 disposed between the rear bracket 8 and the stop 18, and provides a space adapted for the reception of the bail 11 as the same moves rearwardly upon striking the stop 3. This recess further functions to eliminate friction between the keeper 10 and the body 5, as the former is displaced outwardly, and is slid backwardly upon striking the stop 3.

It will be understood, that the shoulder portion 15 formed at the forward end portion of the keeper 10, serves as a means whereby accidental release of the keeper 10 is prevented in the event that the keeper should become entangled in the kite string as the body progresses upwardly thereof. It will also be seen, that as the beveled striking surface 17 engages with the cooperatively beveled surface of the stop 3, the shoulder 15 will be displaced downwardly out of engagement with the forward end portion of the body, thereby permitting the keeper to slide rearwardly of the body within the brackets 7 and 8.

In view of the foregoing, it will be seen that the present invention provides both a useful and novel device for supporting and releasing dropable objects from kite strings, whereby said objects are made to glide or drop earthwardly from the kite to provide both an interesting and educational novelty for the child user. The invention is further characterized by its mechanical efficiency; its simplicity of construction, its ease of operation, and its consequent economy of manufacture.

I claim:

1. In combination with a toy kite and a ground string therefor, a toy-carrying and releasing device comprising an elongated body provided at 60 its upper surface with longitudinally disposed

hook devices adapted for detachable sliding engagement with a kite string to support said body longitudinally thereon, forward and rear guide brackets carried in longitudinal alignment with said body and depending therefrom, said rear bracket being formed with a downwardly open slot, a keeper slidably mounted within said brackets for limited longitudinal movement with respect to said body, said keeper being formed at its rearward end with a downwardly offset bail cooperative with said rear bracket for opening or closing the slot formed therein upon relative longitudinal movement of said keeper with respect to said body and for releasably supporting a droppable toy, said keeper being formed at its forward portion with a shoulder adapted for holding engagement with the foremost end of said body, said shoulder when so engaged serving to prevent longitudinal movement of the keeper with respect to the body, said keeper being formed at its extreme outer end with a beveled striking surface, and a stop adapted for stationary positioning upon said ground string substantially at its kite-receiving end, said stop being formed with a beveled surface cooperative with the striking surface of said keeper, said stop serving upon striking engagement with the forward end of said keeper to disengage said shoulder from said body and to impart longitudinal sliding movement to said keeper thereby effecting the release of a toy carried by said bail.

2. In combination with a toy kite and a string therefor, a toy-carrying and releasing device comprising an elongated body adapted for detachable sliding engagements with a kite string, a pair of brackets disposed substantially at the ends of said body and depending therefrom, one of said brackets being formed with an outwardly opening slot, a keeper slidably positioned in said brackets and extending longitudinally of said body, said keeper being formed at one end with a substantially U-shaped bail cooperative with the slot formed within said bracket for opening the same upon longitudinal sliding movement in one direction, said bail serving as an attachment for a droppable toy, said keeper being formed at its opposite end with a shoulder adapted for holding engagement with an end of said body and a beveled striking surface, said shoulder serving when engaged with the end of said body to prevent longitudinal movement of the keeper with respect to the body, and a stop adapted for stationary attachment to said kite string, said stop being formed with a beveled surface adapted for striking engagement with the beveled striking surface of said keeper to disengage said shoulder from the end of said body and to impart longitudinal sliding movement to said keeper to release the toy carried by said bail.

PAUL C. ARMBRUST.
